(57) **CLAIM**

The ornamental design for a fenestration hardware, as shown and described.

DESCRIPTION

FIG. 1 is a first perspective view of the fenestration hardware, installed in a fenestration assembly, showing the new design.

FIG. 2 is a second perspective view of the fenestration hardware of FIG. 1 in a locked configuration.

FIG. 3 is a front view of the fenestration hardware of FIG. 2.

FIG. 4 is a back view of the fenestration hardware of FIG. 2.

FIG. 5 is a top view of the fenestration hardware of FIG. 2.

FIG. 6 is a bottom view of the fenestration hardware of FIG. 2.

FIG. 7 is a first side view of the fenestration hardware of FIG. 2.

FIG. 8 is a second side view of the fenestration hardware of FIG. 2.

FIG. 9 is a third perspective view of the fenestration hardware of FIG. 1 in an intermediate configuration.

FIG. 10 is a fourth perspective view of the fenestration hardware of FIG. 1 in an unlocked configuration.

FIG. 11 is a sectional view of the fenestration hardware of FIG. 1; and,

FIG. 12 is a fourth perspective view of the fenestration hardware of FIG. 1.

The dot dash dot lines immediately adjacent to the shaded areas represent the bounds of the claimed design. All other broken lines are directed to unclaimed features and form no part of the claimed design.

1 Claim, 8 Drawing Sheets
